UNITED STATES PATENT OFFICE

2,276,578

PAPER CONTAINER

Richard F. Hahn, Easton, Pa., assignor to Dixie-Vortex Company, Easton, Pa., a corporation of Delaware

Original application September 13, 1939, Serial No. 294,762. Divided and this application May 3, 1940, Serial No. 333,226

1 Claim. (Cl. 229—5.6)

My invention relates to new and useful improvements in paper containers and more particularly to a container for milk or other fluids and the present application is a division of my co-pending application filed September 13, 1939, Serial No. 294,762.

The principal object of the invention resides in the provision of a novel form of bottom closure for the body portion of the container, said bottom closure including a flanged portion spaced from the wall of the body and in which space adhesive may be applied for securing the bottom closure within the body and to provide a tight seal.

Another object of the invention resides in the provision of a novel form of bottom closure for the body portion of the container, the body portion being tapered and the bottom closure having a disc-like portion and an outwardly directed flange, the flange being bent at an angle in a direction opposite to the taper of the body, to provide a space between the outer face of the flange and the inner face of the body for an adhesive, said adhesive securely connecting the bottom portion to and within the body portion and providing a tight seal to prevent leakage of the contents of the container.

With the above and other objects in view, which will appear as the description proceeds, my invention consists in the novel details of construction, and arrangement of parts, described in the following specification and illustrated in the accompanying drawing, and while I have illustrated and described the preferred embodiments of the invention, as they now appear to me, it will be understood that such changes may be made as will fall within the scope of the appended claim.

In the drawing—

Fig. 1 is a side elevation of the container with parts broken away; and

Fig. 2 is a fragmental transverse vertical section through the bottom portion of the container with parts shown in elevation.

Paper containers have come into extensive use for various purposes, such as for holding milk or other liquids, and in carrying forward my invention I have had in mind a bottom closure of a form cooperating with the taper of the body portion of the container to provide a space for the reception of adhesive for securely attaching the bottom closure within the body and forming a tight seal to prevent leakage of the contents of the container.

In the drawing 1 indicates the body portion of

the container which is of truncated cone-shape and this body is formed from a blank shaped to provide the overlapped edges 2, the overlapped edges being secured together by a suitable adhesive.

At 3 I have illustrated a bottom closure inserted into the large end of the body and this bottom closure includes the top disc-like portion and a depending flange 4 which is bent to project at less than a 90° angle from the top disc-like portion and as shown in a direction opposite to the taper of the body. Cooperating with the taper of the body 1 the flange 4 provides a space between the outer face of the flange and the inner face of the body to receive the adhesive which is shown at 5. This adhesive secures the bottom closure securely within the larger end of the body and as a considerable amount of the adhesive may be received in the space formed between the outer face of the flange and the inner face of the body a tight seal is provided to aid in preventing leakage of the contents from the container. It will be understood that the bottom closure is positioned inwardly of the bottom edge of the body and the bottom edge is then turned inwardly, as shown at 6, to engage and tightly press against the inner face of the flange 4. As shown in the drawing a certain amount of adhesive 5 will extend below the bottom edge of the depending flange and due to the pressure applied in turning the bottom edge of the body into contact with the inner face of the flange it is possible that some of the adhesive may be forced between the up-turned bottom edge of the body and the inner face of the depending flange. If this is done the adhesive will aid in holding the up-turned edge of the body in engagement with the depending flange of the bottom.

From the above it will be seen that I have provided a novel form of bottom closure for a container in which the bottom closure will be securely held against displacement and provide a tight seal. The bottom closure is inserted into the enlarged end of the body, which is tapered, and will be forced into tight engagement with the inner face of the body, as shown very clearly in the drawing, with the depending flange extending inwardly in a direction opposite to the taper of the body. It can be seen that because of the taper of the body the bottom can only be inserted a determined distance and when in position cannot ride inwardly of the body. Thus it is held in position against movement within the body. By having the depending flange extend-

ing inwardly in a direction opposite to the taper of the body a relatively large space is provided for receiving the adhesive and this adhesive not only secures the bottom within the body but provides a tight seal to prevent leakage of the material in the container between the outer face of the flange and the inner face of the body. Of course, the up-turned bottom edge of the body also aids in forming the tight seal.

A top closure for the container, shown at 1, is in the form of a cap having a depending flange 8 and a tab 9, this tab 9 being provided for tearing a portion of the top closure along the lines 10 and 11. The overlapped edge 2 of the container is shown as being provided with a flap 12 beneath which the tab 9 may be engaged when desired, but as the top closure and the flap 12 form no part of the invention covered by the present application, but is covered in the co-pending application of which the present application is a division, a further detailed description thereof will not be given.

Having fully described my invention what I claim as new and desire to secure by Letters Patent is:

5 A container including a tapered body and a bottom closure having a disc-like portion and an outwardly directed flange, the bottom closure being inserted into the larger end of the tapered body with the flange extending outwardly and that portion of the flange adjacent the disc-like portion contacting with the inner face of the body, the flange being bent at an angle of less than 90° relative to the disc-like portion and in a direction opposite to the taper of the body to provide a space between the outer face of the flange and the inner face of the body from the outer end of the flange to the point of contact with the body and opening towards the larger end of the body, said larger end being folded inwardly around the end of the closure flange and in contact with the inner face thereof and adhesive positioned in and filling said space.

RICHARD F. HAHN.
